UNITED STATES PATENT OFFICE

158,221

PACKAGE STAPLING MACHINE

Travis M. Sasser, Terrace Park, Ohio, assignor to
Shipping Room Suppliers, Inc., Cincinnati,
Ohio, a corporation of Ohio

Application February 11, 1948, Serial No. 144,401

Term of patent 14 years

(Cl. D74—1)

To all whom it may concern:

Be it known that I, Travis M. Sasser, a citizen of the United States, residing at Terrace Park, in the county of Hamilton, and State of Ohio, have invented a new, original, and ornamental Design for a Package Stapling Machine, of which the following is a specification, reference being had to the accompanying drawing, forming a part thereof.

In the drawing:

The figure is a perspective view of a package stapling machine, showing my new design.

What I claim is:

The ornamental design for a package stapling machine, as shown.

TRAVIS M. SASSER.
